ATTORNEY

UNITED STATES PATENT OFFICE.

CHARLES W. WEIR, OF EAST MCKEESPORT, PENNSYLVANIA.

AUTOMOBILE-TANK VALVE DEVICE.

1,364,497.

Specification of Letters Patent.

Patented Jan. 4, 1921.

Application filed March 4, 1920. Serial No. 363,203.

To all whom it may concern:

Be it known that I, CHARLES W. WEIR, a citizen of the United States, residing at East McKeesport, in the county of Allegheny and State of Pennsylvania, have invented new and useful Improvements in Automobile-Tank Valve Devices, of which the following is a specification.

This invention relates to valve devices and 10 has for its principal object to provide an improved valve device for controlling the flow of liquid fuel from the liquid fuel tank of a motor vehicle.

In the accompanying drawing; Figure 1 15 is a sectional view of a gasoline tank for a motor vehicle with my improved valve device applied thereto; Fig. 2 an inverted plan view of the valve device, partly in section, and Figs. 3 to 6, sectional views of the 20 valve device showing the controlling valve in the respective positions of emergency, draining, blow out, and shut off.

In Fig. 1 of the drawing, my improved 25 valve device is shown applied to a gasoline tank 1 and comprises a body 2 having a screw threaded nipple 3 adapted to be screwed into the bottom of the tank 1.

Within the body 2 is a tapered plug valve 4 having a three way port 5 and provided 30 with an operating handle 6, the operating positions of the plug valve being determined by a movable pin 7 which is yieldingly pressed into cavities 8 in the body by a coil spring 9.

Passages 10 and 11 extend from the seat 35 of the valve 4 through the nipple 3 and a small pipe 12 connected to passage 10 extends up into the tank 1 for a certain distance.

A nipple 13 having a passage 14 leading 40 to the seat of the valve 4 is adapted to be connected to the pipe which supplies gasoline from the tank to the usual carburetor of the internal combustion engine and a 45 nipple 15 having a passage 16, leading to the seat of said valve, serves both as a drain connection and as a blow out connection.

In operation, the handle 6 is normally 50 maintained in the service position, as shown in Fig. 1 of the drawing, in which the port 5 in the plug valve 4 connects passage 10 with passage 14, so that gasoline in the tank 1 is free to flow through the nipple 13 to the carburetor of the engine until the level of

the gasoline in the tank falls below the top 55 of the pipe 12.

If the level of gasoline should be allowed to fall to the level of the top of pipe 12, the gasoline supply to the carburetor will be cut off and the operator will thus be warned that 60 his fuel supply is low. He can then turn the handle 6 to emergency position, as shown in Fig. 3 of the drawing, in which the port 5 in the valve 4 connects passage 11 as well as passage 10 with passage 14.

All of the gasoline in the tank may now 65 be supplied to the carburetor and this will provide sufficient fuel to operate the car so as to reach a gasoline supply station.

If it is desired to drain the tank 1 for 70 cleaning purposes or if a supply of gasoline is required, the handle 6 is turned to the drain position, as shown in Fig. 4 of the drawing, in which the port 5 connects passage 11 with passage 16.

The blow out position, as shown in Fig. 5 75 of the drawing, is particularly desirable, as in this position, the port 5 connects passage 16 with passage 14 and by attaching a hand pump to the threaded nipple 15, the gasoline feed pipe to the carburetor may be blown out and any dirt or other obstructions in the pipe may be blown out. Since 80 all of the other passages are now closed, no leakage can occur.

In the position of the plug valve, as 85 shown in Fig. 6 of the drawing, all of the passages are closed and this position may be useful in case of feed pipe breakage or the like, when it is desired to cut off all flow of 90 gasoline from the tank 1.

Having now described my invention, what I claim as new and desire to secure by Letters Patent, is:—

1. A valve device for a liquid fuel tank 95 of a motor vehicle comprising a valve body having an inlet passage leading to the tank, an outlet passage and a blow out passage, and a valve for connecting the inlet passage with the outlet passage in one position and 100 the blow out passage with the outlet passage, in another position.

2. A valve device for attachment to a motor vehicle gasoline tank comprising a valve body having an outlet passage and a 105 drain passage and a valve in said body having one position for connecting the tank with the outlet passage, another position for

connecting the tank with the drain passage for draining the tank, and a third position for connecting the drain passage with the outlet passage for blowing air under pressure through the outlet passage.

- 5 3. A valve device for attachment to a motor vehicle gasoline tank comprising a valve body having an outlet passage, a tank inlet passage, and a drain passage, and a 10 valve in said body having one position for connecting the inlet passage with the outlet passage, another position for connecting the inlet passage with the drain passage, another position for connecting the drain passage with the outlet passage, and a position in which all said passages are closed.

- 15 4. A valve device for attachment to a motor vehicle gasoline tank comprising a valve body having a high tank level inlet 20 passage, a low tank level inlet passage, an outlet passage and a drain passage, and a valve in said body having one position for connecting the high level passage with said outlet passage, another position for connecting the low level inlet passage with the drain passage, another position for connecting the drain passage with the outlet passage, and another position in which all said 45 passages are closed.

necting the low level inlet passage with the 25 outlet passage, another position for connecting the low level inlet passage with the drain passage, and another position for connecting the drain passage with the outlet passage.

30

5. A valve device for attachment to a motor vehicle gasoline tank comprising a valve body having a high tank level inlet passage, a low tank level inlet passage, an outlet passage and a drain passage, and a 35 valve in said body having one position for connecting the high level passage with said outlet passage, another position for connecting the low level inlet passage with the outlet passage, another position for connect- 40 ing the low level inlet passage with the drain passage, another position for connecting the drain passage with the outlet passage, and another position in which all said 45 passages are closed.

In testimony whereof I have hereunto set my hand.

CHARLES W. WEIR.
